UNITED STATES PATENT OFFICE.

PHILIP LAUT, OF NEW YORK, N. Y.

ROTARY BLOWER.

950,856.

Specification of Letters Patent. Patented Mar. 1, 1910.

Application filed October 16, 1909. Serial No. 522,920.

To all whom it may concern:

Be it known that I, PHILIP LAUT, a citizen of the United States of America, residing in New York, in the borough of Brooklyn, county of Kings, and State of New York, have invented certain new and useful Improvements in Rotary Blowers, of which the following is a specification.

This invention relates to an improved rotary blower in which the impellers are protected against wear by friction with the casing, without requiring adjustment at their centers and without requiring the removal of the impellers for replacing them with new ones.

The invention consists of a rotary blower the impellers of which are provided with detachable heads that are cushioned by a block of elastic material interposed between the body and head and held in position by center-pins and fastening screws so as to keep the heads of the impellers in tight contact with each other and with the interior surface of the casing, and take up the wear of the same.

In the accompanying drawing, Figure 1 represents a front-elevation of a rotary blower, and Fig. 2 is a vertical transverse section on line 2, 2, Fig. 1, showing the rotary impellers in vertical transverse section.

Similar letters of reference indicate corresponding parts throughout the views.

Referring to the drawing, C represents the casing of a rotary blower which is composed of two semi-cylindrical portions C¹ that are connected by a straight intermediate portion C² which is provided with the usual suction and discharge-openings. In the cylinders of the casing C are arranged the impellers B, B¹ which are of any approved shape, so that the head of one impeller fits tightly into the concavity of the other impeller and to the interior surface of the cylindrical portion C¹. The impellers are supported in the usual manner on shafts S S¹ which turn in bearings in journal-boxes in the heads of the casing, and which are driven by suitable gearing from an electric or other motor M. Each impeller B B¹ is made of a central concave or body portion b and separate detachable heads b¹. Between the body-portion b and the heads b¹ are interposed blocks r of soft rubber or other elastic material which are provided with a plurality of center-holes o for the passage of pins p that are inserted

into sockets of the body-portion b, said pins entering corresponding sockets p¹ in the heads b¹, after placing the elastic blocks in position thereon. The outer edges of the elastic blocks f¹ are ground off in line with the contours of the curved body-portions and heads. The heads b¹ are further connected with the body-portion by means of screw-bolts d which are screwed into tapped holes d¹ of the body-portion, the heads of the screw-bolts resting on short sleeves d² placed in bores b² which are drilled parallel with the longitudinal axis of the impeller and closed at their outer ends by means of plugs d³, the ends of which are trimmed off so as to be in line with the curvature of the heads b¹. The screw-plugs d³ serve for preventing any dust or other sediment to settle in the bore-holes b², and also for preventing the escape of any screw-bolt d which may become loose by the vibration of the rotating impellers.

The elastic blocks serve to keep the heads of the impellers tightly in contact with the casing C and also in tight contact with the concaved sides of the body-portions b. When after extended use, the heads of the impellers should wear off, or the elastic blocks diminish slightly in thickness by the pressure of the heads on the same, a thin steel-plate e is interposed between the end or ends of the body b of the impeller and the adjacent block or blocks r, said plate being of the same size as the face of the body of the impeller and provided with holes corresponding to the center-pins p and screw-bolts d employed. When after some time the wear of the heads of the impellers is again noticeable, a second, or even a third, steel-plate may be inserted so as to take up the wear. In Fig. 2, one of the heads b¹ is backed up by a steel-plate e. This insertion of the steel-plates for taking up the wear of the heads has to be done when an inspection of the impellers on opening the casing of the blower shows that it is necessary to take up the wear and produce a tighter contact between the heads of the impellers and the interior surface of the casing.

It is obvious that the improved impeller can also be used for gas-exhausters and pumps, and dispense with all exterior adjustment of the shafts and other devices for producing a tight fit between the impellers and their casing.

Having thus described my invention, I claim as new and desire to secure by Letters Patent:

1. An impeller for rotary blowers etc., consisting of a body-portion, detachable heads, elastic blocks interposed between the body-portion and heads and extending to the full width of the same, means for centrally connecting the elastic blocks and heads, and means for fastening the heads and blocks to the body.
2. In rotary blowers etc., an impeller consisting of a body-portion and detachable heads, elastic blocks interposed between the body-portion and heads and extending to the full width of the same, fixed center-pins passing through the elastic blocks into sockets of the heads, and means for fastening the heads and blocks to the body-portion.
3. In rotary blowers etc., an impeller con-

sisting of a body-portion and detachable heads, said heads being provided with bores parallel with the longitudinal axis of the impeller, elastic blocks interposed between the body-portion and heads and extending to the full width of the same, center-pins passing from the body-portion through the elastic blocks into sockets of the heads, screw-bolts passing through bores in the heads and elastic blocks into the body-portion, and screw-plugs in the outer ends of the bores in the heads.

In testimony, that I claim the foregoing as my invention, I have signed my name in presence of two subscribing witnesses.

PHILIP LAUT.
